Primary Examiner — Katie Jane Stofko**(57) CLAIM**

The ornamental design for a jersey-shaped stand and grip, as shown and described.

DESCRIPTION

FIG. 1 is a top, front, right side view of a first embodiment of a jersey-shaped stand and grip showing my new design; FIG. 2 is a top, front, right side view of a second embodiment of a jersey-shaped stand and grip showing my new design;

FIG. 3 is a right side elevation view thereof;

FIG. 4 is a right side elevation view thereof, shown in a collapsed position;

FIG. 5 is a top plan view thereof;

FIG. 6 is a bottom plan view thereof; and,

FIG. 7 is a rear elevation view thereof.

The broken lines shown in FIGS. 1-7 illustrate portions of the jersey-shaped stand and grip that form no part of the claimed design.
